I. CLAIR.
SAFETY RAZOR.
APPLICATION FILED JUNE 11, 1919.

Patented Feb. 8, 1921.

UNITED STATES PATENT OFFICE.

ISIDORE CLAIR, OF BROOKLYN, NEW YORK.

SAFETY-RAZOR.

1,368,116.

Specification of Letters Patent.

Patented Feb. 8, 1921.

Application filed June 11, 1919. Serial No. 303,305.

To all whom it may concern:

Be it known that I, ISIDORE CLAIR, a citizen of the United States, and a resident of the city of New York, borough of Brooklyn, 5 in the county of Kings and State of New York, have invented a new and Improved Safety-Razor, of which the following is a full, clear, and exact description.

My invention relates to safety razors, and 10 aims more particularly to provide a device of this nature in which all possibility of the user cutting himself is eliminated.

A further object of the invention is the provision of means associated with the razor 15 whereby certain portions of the head and face may be brought into the line of vision while the razor is in use.

It is well appreciated among the users of safety razors that a detrimental feature of 20 almost all of the present razors upon the market is that the corners of the blade are not amply protected, so that upon the razor being held at a certain angle, and a stroke being executed, a very painful cut will be 25 inflicted upon the skin of the user.

In view of the foregoing, I have, therefore, devised a guard aiming to overcome 30 this defect of present razors, by reason of such guard protecting the corners of the blade and keeping them out of cutting contact with the surface of the skin at all times.

A still further object of the invention is the provision of means which will normally retain the cutting blade of the razor in 35 proper contact with the surface of the skin.

It is, further, well appreciated among 40 razor users of any type that it is almost impossible for the operator of a razor to handle the same in such a manner as to properly shave the back of his neck. Also, even with the aid of a mirror, it has been difficult to bring the edge of the razor blade into engagement with the surface of the skin at the exact point where the beard begins and the hair terminates, as this portion 45 of the face is hidden by the hand which is holding the razor, under normal conditions, and the proper position of the razor must be determined more or less by instinct.

50 Figure 1 is an end view of a razor showing the blade in unseated position;

Fig. 2 is an enlarged bottom view of the head;

55 Fig. 3 is an elevational view of the blade seat and guard;

Fig. 4 is a side view of my razor showing

the handle therefor optionally attached to the end or under face of the guard;

Fig. 5 is a sectional view taken through the head of the razor and showing the blade 60 in seated position and the handle attached to the end of the guard;

Fig. 6 is a side view of the razor with my reflector or mirror attached thereto;

Fig. 7 is an end view of a razor with said 65 reflecting attachment applied; and

Fig. 8 is a section taken along line 8-8 of Fig. 7.

In all of these views like reference numerals designate similar parts and the reference 70 numeral 1 indicates a handle, which may be optional, of a construction hereinafter more fully specified, attached either to the underside or to the head of the razor. This head includes a blade seat 2 formed with outwardly-extending lugs 3. The blade 4 is placed upon the seat 2 and is held in applied position by means of a blade-depressing element 5, which blade-depressing element is preferably formed with a curved 75 under surface and an upper surface divided into two inclined portions, and is further provided with pins 6 adapted to project through openings 7 formed through the blade seat 2 when the blade-depressing element 80 is drawn into proper position by means of the handle 1 having its screw-threaded socket, with which it is provided, engaging the stud 8 projecting downwardly from the blade-depressing element 5, similar 85 to the Gillette type of razor.

The aforementioned construction is utilized where the handle 1 is attached, in the position illustrated in Figs. 1 and 6, to the head; but assuming that it is desired to 95 apply the handle 1 to the head in the manner indicated in the lower part of Fig. 4, as in Fig. 5, associated with my handle 1 is a double-ended screw 10 whose inner end screws into the screw-threaded opening in 100 the upper end of the handle and whose upper part engages any screw threads formed in a projection such as 11 at any convenient part of the blade seat 2.

It will readily be understood that if I 105 should combine the elements as just described, the blade and its associated seat would not remain in their proper position, but the swinging nature of the blade 4 would tend to force the blade-depressing element 110 5 from out of contact with the blade seat 2, for the reason that the blade would not be

in proper position for shaving. To overcome this defect, when I apply my handle to the end of the head I retain the head-depressing element in its proper position by 5 means of a hand nut 12 which engages the stud 8 projecting downwardly from the blade-engaging element 5. It will readily be appreciated that upon rotation of the nut 12, by virtue of the latter being mounted 10 upon the stud 8 and engaging with its upper edges the underside of the blade seat 2, said blade seat and blade-depressing element would be drawn together whereby to retain the blade 4 in proper position.

15 Referring now more particularly to the reflecting attachment 13 utilized in connection with my razor, I would point out that the same may be any suitable metallic or non-metallic reflector, which is bent inwardly through its central portion so as to 20 present two reflecting surfaces 14 and 15 to the eye of the user.

As is illustrated in Fig. 6 of the attached sheet of drawings, the reflecting attachment 25 13 may be secured to the blade seat 2 by means of any suitable attaching means, such as screws 9, the attachment being arranged at such an angle to the handle as to terminate adjacent thereto, as clearly shown in 30 Fig. 6.

In operation it will now be appreciated, 35 assuming that the handle has been attached to the head in the manner illustrated in Fig. 1 and that the blade-depressing element 5 has been drawn toward the blade seat 2 by means of the rotation of such handle, the blade will now be in the position illustrated 40 in Fig. 5. Contrary to the usual method of procedure, the razor handle in this instance 45 is held outwardly at almost right angles to the face of the user, the inclined upper surface of the blade-depressing element 5 serving as a guide for the blade and blade seat 2, together with its lugs 3, and serves as an effectual guard against any danger of cutting the user's face.

Assuming now that the purchaser desires 50 to utilize my razor similarly to the operation of a safety razor of the Durham Duplex type, it will readily be appreciated that this may be done by simply detaching the han-

dle 1 from the head and applying thereto the double-ended screw 10. Before the shaving operation is attempted, the nut 12 is applied to the stud 8 and rotated, whereby 55 to properly position the head with respect to the blade seat. In this instance the upper end of the double-ended screw 10 will enter into the screw-threaded opening formed in the projection 11 and the razor may now be 60 employed as an ordinary straight razor, if so desired.

Applied to the head of the razor, and preferably attached along its upper edge, is a mirror, as indicated by the reference 65 numeral 16, which terminates at a point slightly spaced from the handle 1.

I wish it understood that any number of modifications may be resorted to without in the least departing from the scope of my 70 invention, as for instance, eliminating the projection from the head so that the razor may be utilized in the same manner as that of the standard Gillette type. It might also be utilized with or without the mirror 75 16. Further, it will be appreciated that I might readily within the scope of my invention, produce razors of the standard Durham Duplex type similar to the attachment illustrated in the lower part of Figs. 80 4 and 5, and that the handles may be formed integral with the heads, if it is so desired.

Having thus described my invention, I desire to claim:

1. A razor, including a head portion, a handle associated with such head portion, and a mirror attached to and extending downwardly from said head portion.
2. A razor, including a body portion, a handle associated with said body portion, and a mirror having its upper end secured to said body portion and having its lower end extending inwardly and downwardly therefrom.
3. A razor, including a body portion, a handle associated with said body portion, and a mirror having its upper end secured to said body portion and having its lower end extending inwardly therefrom, such mirror being subdivided into two separate 100 surfaces at an angle one to the other.

ISIDORE CLAIR.
